UNITED STATES PATENT OFFICE

MARCUS H. RHODES, OF NEW HAVEN, CONNECTICUT, ASSIGNOR TO M. H. RHODES, INC.,
OF NEW HAVEN, CONNECTICUT, A CORPORATION OF DELAWARE

SIGNAL

Application filed February 14, 1931. Serial No. 515,727.

This invention relates to signals and with regard to certain more specific features, to signals for indicating the expiration of a predetermined interval of time.

5 Among the several objects of the invention may be noted the provision of a signal of the class described which is adapted to ring a bell or perform a similar function at the expiration of a period of time predetermined by adjustable means on the signal; the provision of a signal of the class described which may be set in operation or disconnected at will; a signal of the class described which is adapted to react quickly and positively without depending upon the delicate timing mechanism per se for the impulsion which effects the signal; the provision of a signal of the class described which is simple and accurate in operation; the provision of a combination including a signal of the class described and an electric switch whereby a variety of functions may be performed at the expiration of the predetermined time interval; and the provision of a signal of the class described which is simple in construction and operation, and which requires a minimum number of complicated, moving parts. Other objects will be in part obvious and in part pointed out hereinafter.

20 The invention accordingly comprises the elements and combinations of elements, features of construction, and arrangements of parts which will be exemplified in the structure hereinafter described, and the scope of 25 the application of which will be indicated in the following claims.

In the accompanying drawings, in which is illustrated one of various possible embodiments of the invention.

40 Fig. 1 is a plan view of a flush face plate carrying a signal embodying the present invention;

Fig. 2 is a side elevation of the signal and face plate shown in Fig. 1;

45 Fig. 3 is a side elevation similar to Fig. 2, with certain parts removed;

Fig. 4 is a cross section taken substantially on line 4—4 of Figs. 2 and 3;

50 Fig. 5 is a cross section taken substantially on line 5—5 of Fig. 4;

Fig. 6 is an ideal section taken along line 6—6 of Fig. 5;

Fig. 7 is a fragmentary section taken on line 7—7 of Fig. 5; and,

Fig. 8 is a cross section similar to Fig. 5 showing the signal in advanced condition of operation.

Similar reference characters indicate corresponding parts throughout the several views of the drawings.

Referring now more particularly to Fig. 1, there is illustrated at numeral 1 a cover plate for the present signal. In the illustrated embodiment, the cover plate 1 is similar in appearance to a flush face plate generally used for mounting of electrical switches and the like. Centrally disposed in the cover plate 1 is an opening 3 which permits the passage of a control handle 5 to available manipulating position. A second opening 2 in the cover plate 1 permits the passage of a time control lever 4 to available manipulating position. A third opening 6 in the plate 1 is provided for the purpose of reading suitable indicia on an indicator wheel 113 for establishing a time interval as will be described hereinafter.

Supported on the cover or face plate 1 by means of screws 9 is a switch 7. From the exterior, the switch 7 will be seen to comprise a mounting plate 11 (with which the face plate screws 9 engage) and a switch housing 13 having exterior connecting terminals 15 and 17 mounted thereon. Screws 19 (see Figs 4 and 5) hold the housing 13 to the mounting plate 11.

The interior construction of the switch 7 will be seen in Figs. 4, 5 and 6. The mounting plate 11 has extending at right angles therefrom a pair of sideward portions 21 and 23. A plate 25, which is shaped with substantially the same form as the housing 13, is attached to portion 23 by means of rivets or spot welding or the like as indicated at numeral 27 (Fig. 5). Mounted at one side 95 in the plate 25, and at the other side in the sideward portion 21, is a pin 29, upon which the control handle 5 is rotated.

The switch control handle 5 comprises a semi-circular portion 31 from which extends

60

65

70

75

80

85

90

95

100

a knob 33 for manipulation purposes. The back, concealed (in the assembled switch) portion of the switch 5 is reduced in thickness as at numeral 35 (Figs. 5 and 6) and has a 5 contour including a projection 37 having a nose 39 thereon, and a depression, or hollowed-out portion 41. The pin 29 upon which the handle 5 is rotated passes through the thin portion 35, in the region of the projection 37.

Mounted rigidly on the switch handle 5, embracing the thin portion 35 thereof, and extending into the depression 41, is a saddle member 43. This saddle 43 comprises a pair 15 of legs 45, which fit snugly against the sides of the handle 5, and a cross-piece 47 at right angles to the legs 45. The pin 29 passes through the legs 45. The cross-piece 47 engages the nose 39 of the projection 37 of the 20 switch 5, whereby the saddle 43 is, relative to rotation on the pin 29, fixed to the handle 5. That is to say, the saddle 43 is mounted on the handle 5 in a fixed, non-rotatable manner. The cross-piece 47 is provided with a 25 nose 49 which engages one end of a compression spring 51 to be described more in detail hereinafter.

Associated with the saddle 43 is a movement limiting means for the handle 5 (see 30 Fig. 7). The movement limiting means per se comprises a flat "h" shaped piece 53, having parallel legs 55 and 57, and a single extending leg 59. The leg 55 passes loosely through a pair of holes 61 in the legs 45 of 35 the saddle 43. The single extending leg 59 passes through a slot 63 having a predetermined length in the plate 25, and projects a short distance beyond said plate 25 for winding purposes as will be described more fully 40 hereinafter. Considering that the saddle 43 is fixed to the handle 5, and that the plate 25 is relatively a part of the stationary ground wherein the handle 5 rotates, it will be seen that engagement of the single extending leg 59 with the ends of the slot 63 limits 45 the rotation or movement of the handle 5.

Also mounted on the pin 29, in this instance rotatably mounted, is a second saddle 65 embracing the saddle 43. The saddle 65, 50 hereinafter termed the hammer saddle, comprises a pair of relatively long legs 67, through which the pin 29 passes (loosely enough to permit of ready rotation), and a hammer portion 69 at right angles thereto. 55 The hammer portion 69 has a nose 71 thereon which engages the other end of the compression spring 51. Movement of the hammer saddle 65 is limited by a pair of ears 73 struck from the plate 25. Formed at the 60 moving end of the hammer saddle 65 is a clapper arm 74 which projects through a slot 76 in the housing 13 in suitable position to strike a bell 78 supported on the housing 13 by means of a pillar or the like 80.

65 It will be seen that the saddles 43 and 65

together with the compression spring 51 comprise an overcentering toggle. In Fig. 5, motion of the handle 5 in a leftward direction, through the saddle 43, compresses the spring 51 against the saddle 65, which is immovable 70 because of its engagement with the right-hand ear 73, until the saddles 43 and 65 pass the parallel position, at which time the compressed spring reacts to suddenly throw the hammer saddle 65 to the left against the left-hand movement-limiting ear 73 (see Fig. 8). A similar reaction and overcentering action causes the hammer saddle 65 to snap sharply 75 from its Fig. 8 to its Fig. 5 position, when the handle 5 is moved to the right from its Fig. 8 position.

In the present embodiment, the signal means comprising the present invention is shown as combined with an electrical switch. It is to be understood, however, that the invention includes the elements heretofore described alone, without the addition of the electrical contacting means to be described hereinafter. In other words, the signal may be operated only as a signal without effecting 90 any electrical circuit making and breaking, or it may be combined as illustrated, with an electrical switch adapted to be operated at the time the signal is effected.

The electrical connections in the present embodiment of the signal will be seen particularly in Figs. 4 and 5. The exterior terminals 15 and 17 comprise, respectively, metallic strips 75 and 77 which are held to the housing 13 by means of screws 79, and which receive in threaded engagement screws 81. By means of the screws 81, exterior connections to the switch are made. The metallic strip 75 extends into the housing 13, spaced from the side wall thereof, and is provided with a slanting knife-edge contacting portion 83. The metallic strip 77 extends into the housing 13, also spaced from the side wall thereof, and is provided with a knife-edge contacting portion 85 similar to the contacting portion 83, but facing oppositely.

Formed in interior of the housing 13 is a protruding ear 87. A pin or shaft 89 passes through the side of the housing 13 and threadedly engages the ear 87 (see Fig. 6). On the pin 89 is rotatably mounted a contactor bar-anvil assembly 91. The parts of the assembly 91 are non-rotatable or otherwise movable relative to each other, but the assembly as a whole rotates freely on the pin 89.

The assembly 91 comprises an anvil piece 93 and a contactor bar 95, together with suitable spacing washers, all mounted on a sleeve 97 through which passes the pin 89. The anvil piece 93, preferably formed of insulating material, includes a notch 99 which engages the hammer portion 69 of the hammer saddle 65 (see Fig. 5). The contactor bar 95 comprises a pair of spring-metal strips 125 130

101 shaped to engage and disengage, by rotation on the pin 89, the knife-edge contacting strips 83 and 85. The relative shape of the bar 95 and the spacing of the contacting 5 strips 83 and 85 will be apparent from Fig. 5.

As the hammer saddle 65 snaps from one position to the other, as described hereinbefore, the clapper arm 74 is caused to strike sharply against the bell 78, thus effecting a 10 musical note or signal. Simultaneously with the ringing of the bell 78, the hammer saddle 65, on account of its engagement with the notch 99 in the anvil piece 93, causes the assembly 91 to rotate as a whole on the pin 89 15 and consequently causes the contactor bar 95 to rotate into and out of contact with the pieces 83 and 85. Thus, establishing of a signal and contemporaneous making and breaking of an electrical connection from 20 terminal 15 to terminal 17 are effected in a sudden, snap-acting manner by simple movement of the switch control handle 5.

The foregoing description has been made without regard to the time controlling mechanism which is adapted to permit the hammer saddle 65 to swing only upon expiration of suitable, adjustable, periods of time. The time controlling mechanism is indicated generally by numeral 105 in Fig. 4. So far 25 as the present invention is concerned, it is not necessary to describe in detail this time controlling mechanism 105; the details of its construction may be found by reference to my Patent Number 1,773,697 dated August 30 7, 1930.

Broadly described, the timing mechanism 40 105 includes a main spring which is wound by manipulation of the control handle 5, whereby engagement of the projection 59 of the "h" shaped portion 53 with a ratchetwheel 45 107 on the main spring shaft of the timing train, is brought about. The projection 59 is permitted freely to operate in this manner, as the slot 63 is wide enough (see Figs. 5 and 8) to permit lateral movement of said projection as it rides over successive teeth on its backwards stroke. A suitable coil spring (see Fig. 7) is desirably provided to urge the projection 59 against the ratchet wheel 50 107 at all times. A gear train indicated generally by numeral 109, and an escapement mechanism 111 at the end of the gear train 109 permit the main spring to unwind only 55 at a slow rate after it has been wound by manipulation of the control handle 5.

It will be seen that the amount of winding or extent of torque placed in the main spring is a function of number of times the control handle 5 is manipulated. Further, the torque 60 in the main spring is a function of the angular displacement of its shaft. For purposes of indicating the amount of torque placed in the main spring and consequently for providing an indication of the amount of time 65 during which the time control mechanism

will function, the indicator wheel 113 is provided having suitable indicia thereon. These indicia are viewed from the front of the signal through the opening 6 in the face plate 1.

By means of a suitable lug on a portion of the gear train 109, a latch lever 115 is rotated. The lever 115 has a projection or latch 70 75 117 thereon which extends through the plate 25 and is positioned in a location adapted to intercept the motion of the hammer saddle 65. The lever 115 is fixedly attached to a pin 119, which has projecting therefrom the time control lever 4.

Referring more particularly to Fig. 5, it 80 will be seen that the latch 117 is rotated into and out of engagement with the hammer saddle 65 through an arc determined by a slot 118 in the plate 25. When the latch 115 is in its lower position, it does not intercept movement of the hammer saddle 65, which is accordingly permitted to swing freely under the control of the main handle 5. However, when the latch 115 is in its upper position, it acts to intercept rightward motion of the 85 hammer saddle 65.

The lever 4 is arranged so that by manipulation thereof, the latch 117 can be brought into and out of engagement with the hammer saddle 65. Further, the time control mechanism 105 is adapted to push said latch 117 downwardly to disengage the hammer saddle 65 after the expiration of a predetermined interval of time, as described more fully in my 90 said patent.

The operation of the present invention is 100 as follows:

With the time lever 4 set to its "Off" position, manipulation of the control handle 5 swings the hammer saddle 65 as described 105 110 ringing the bell 78 and making and breaking electrical contact. However, when the lever 4 is moved to "On" position, moving of the control handle 5 from "Off" to "On" position results in winding the main spring and moving the latch 117 into position to intercept the motion of the hammer saddle 65, so that upon return of the control handle 5 to its "Off" position the hammer saddle 65 does not swing until a predetermined time has 115 elapsed. The time delay is a function of the number of times the control handle 5 is manipulated, as described in said patent. After the timing mechanism has run down to normal, or rest position, the latch 117 is removed from the path of the hammer saddle 65 and said saddle is permitted to swing, under influence of the compression spring 51, to ring the bell 78 and break the electrical circuit.

As has been pointed out hereinbefore, it is to be understood that the electrical portion of the signals may be disposed of through the simple removal of the terminals 15 and 17 and the contactor bar 95 and its assembly. In such event, the device functions only as a signal, ringing the bell 78 without effect-

ing any electrical connections or disconnections.

It will of course be understood that forms of mounting, such as the face plate 1 and the housing 13 may be substituted for by suitable other forms of encasings, without departing from the spirit of the invention.

The present invention is particularly adapted for installation on large machines and the like, where a time delay is essential to proper manipulation of the machine. In such installations, it is to be noted that the control handle 5 may be connected by a suitable linkage to some moving part of the machine so that the winding of the signal is accomplished by the movement of the machine itself and no manual operation thereof is necessary. Similarly, the time interval or time delay, after which the signal is effected, may be regulated by suitably designing the time delay mechanism 105.

In view of the above, it will be seen that the several objects of the invention are achieved and other advantageous results attained.

As many changes could be made in carrying out the above constructions without departing from the scope of the invention, it is intended that all matter contained in the above description or shown in the accompany drawings shall be interpreted as illustrative and not in a limiting sense.

I claim:

1. A signal comprising a bell, a clapper adapted to strike said bell, a time delay means, a latch controlled by said time delay means adapted to prevent operation of said clapper to strike said bell until a predetermined time interval has elapsed, a lever adapted to throw said latch into and out of position regardless of said time delay means, and a control handle adapted, on movement in one direction, to position said clapper for striking said bell, and on movement in the other direction, to throw said clapper in a direction for striking said bell.

2. A time-delay signal device comprising a bell, a reciprocable control handle, a reciprocable hammer saddle, and an over-centering spring between said handle and said hammer saddle, a clapper associated with said hammer saddle and extending into a position adapted to strike said bell, and a time-controlled latch positionable to intercept and prevent reciprocation of said hammer saddle for a predetermined time interval, upon the expiration of which interval said hammer saddle is actuated by said spring to move said clapper to strike said bell.

3. A device as in claim 2, in which the latch is associated with and operated by an escapement and timing train, said timing train being empowered to action by reciprocation of said control handle.

4. A device as in claim 2, in which the

latch is associated with and operated by an escapement and timing train, said timing train having a motivating main spring, and means connecting the said control handle and said timing train whereby reciprocation of said control handle winds said main spring, in such manner that the extent of winding of the main spring is proportional to the number of reciprocations of the control handle.

5. A device as in claim 2, in which further means are provided for optionally rendering said latch inoperative to intercept said hammer saddle.

In testimony whereof, I have signed my name to this specification this 10th day of February, 1931.

MARCUS H. RHODES.
